UNITED STATES PATENT OFFICE.

HENRY GEISENHÖNER, OF SCHENECTADY, NEW YORK, ASSIGNOR TO GENERAL ELECTRIC COMPANY, A CORPORATION OF NEW YORK.

ATTACHING-PLUG.

No. 896,005.

Specification of Letters Patent.

Patented Aug. 11, 1908.

Application filed August 22, 1903. Serial No. 170,377.

To all whom it may concern:

Be it known that I, HENRY GEISENHÖNER, a citizen of the United States, residing at Schenectady, in the county of Schenectady, 5 State of New York, have invented certain new and useful Improvements in Attaching-Plugs, of which the following is a specification.

The object of the present invention is to 10 provide an improved attaching plug which may be readily inserted in the ordinary incandescent lamp socket or receptacle without rotation, and by which the electric circuit may be completed or broken without 15 disturbance of the plug in relation to the socket or receptacle.

In carrying out my invention I provide a base of insulating material adapted to be thrust longitudinally into the contact-shell 20 of an ordinary lamp socket or receptacle upon which are mounted a center contact and a spring-blade side contact movable radially by a key into engagement with the inner surface of the contact shell of the 25 socket or receptacle, and on the outer end of which are mounted suitable binding posts respectively connected to the center and side contacts and to which the electric conductors may be secured in the usual manner.

For a more complete understanding of my 30 invention reference may be had to the following description and the accompanying drawing forming a part of this specification, in which

Figure 1 is a longitudinal section of a lamp shade and holder and a side elevation of a socket with an attaching plug embodying my invention connected thereto; Fig. 2 is a broken longitudinal section of the at- 35 taching-plug drawn to a slightly larger scale; Fig. 3 is an elevation of the front end of the base part with the key shaft and cover-holding screw shown in section; and Fig. 4 is an inner-end elevation of the plug base.

The base 1 of the attaching-plug is made of 40 porcelain or other suitable insulating material, and is formed with a larger cylindrical outer section 2 and a smaller cylindrical inner section 3 with an intervening shoulder 4. The outer end is provided with a cup-shaped recess 5, from the bottom of which extend an axial aperture 6 to the inner end of the plug and a rectangular side aperture 7 to the shoulder 4 from which it continues along the 45 side of the inner section 3 in the form of an

open channel 8. The inner section 3 is of a size to freely pass longitudinally without relation into the contact-shell of the ordinary lamp socket and is provided with an inner end in a plane at right angles to its axis, having its peripheral corner chamfered and the portions about the central aperture 6 counter-sunk.

A center contact consisting of a metallic washer 9 with its central portion struck up 55 and adapted to enter the counter-sunk end of the aperture 6 and having a circular slit 10 between the struck-up portion and its periphery whereby a portion of the outer edge is rendered free to be permanently bent 60 up out of the plane of the main portion of the washer to form a yieldable contact surface. The washer 9 is secured to the end of the plug by means of a screw 11 extending therethrough, through the axial aperture 6 and 65 engaging a tapped hole in a terminal plate 12 in the bottom of the recess 5.

The plate 12 has two arms disposed at right angles, in one of which is provided a binding screw 13, and in the other a tapped hole for the reception of the cover-holding screw 14. A second terminal plate 15 is secured in the recess 5 by a screw 16 and provided at one end with a binding-screw 17. To the opposite end of the plate 15 is secured 70 a spring contact blade 18 which extends through the side aperture 7 and the open channel 8 to near the inner end of the plug. The blade is provided with corrugations 19 which correspond with the threads on the 75 contact shell of the standard Edison socket and are designed to hold the plug from pulling out when the blade has been forced into electrical contact with the socket contact shell. The opposite side of the small section 80 of the base may be provided with a series of short grooves 20 to engage the thread on the opposite side of the socket shell so as to 85 overcome the tendency of the plug to cant to one side. The cover 21 is also made of porcelain or other suitable insulation, and is 90 formed with a diameter equal to that of the larger section of the base and has a central aperture 22 for the passage therethrough of the conductor wires, a side counter-sunk hole 95 23 for the holding-screw 14, and on the opposite side a cylindrical aperture 24.

The means for forcing the spring contact blade 18 outward into engagement with the contact-shell of the socket consists of a key 100

25 comprising a shank 26 extending through the aperture 24 of the cover and lying in a groove 27 formed on the inner wall of the side aperture 7 and channel 8, and provided at its 5 inner end with a nib or projection 28 which engages at its end with the back of the contact blade when turned. The outer end of the key is provided with a thumb-piece 29 of molded insulation, and at the inner face of 10 the cover its shank is circumferentially grooved for the reception of a spring washer 30 which serves to hold the key from longitudinal displacement relative to the cover.

In order that the key may be arrested 15 when the nib 28 is at the highest point of its arc of travel, a stop 31 is provided upon the contact blade 18 in its path of rotation.

As is apparent from Fig. 1 the attaching-plug may be inserted and clamped in permanent engagement with the contacts of the 20 lamp socket without removal of the lamp-shade, as would ordinarily be necessary in connecting the attaching-plugs heretofore in use. Moreover, in case it be connected to a 25 keyless socket or receptacle the circuit may be readily broken without removal of the plug by merely turning its key to permit the spring contact blade to move inward out of engagement with the contact shell of the 30 socket or receptacle.

I do not wish to limit myself to the particular shape or arrangement of parts shown and described, for it is apparent that they may be changed and modified without departing from my invention.

What I claim as new and desire to secure by Letters Patent of the United States, is:

1. An attaching-plug comprising an insulating base adapted to be thrust endwise into 40 a socket or receptacle, metallic end and side contacts mounted on said base, and hand-operated means to move one of said contacts outward.

2. An attaching-plug comprising an insulating base adapted to be thrust endwise into 45 a socket or receptacle, metallic end and side contacts mounted on said base and means for forcing said side contact radially outward.

3. An attaching-plug comprising an insulating base having a reduced section adapted 50 to be thrust endwise into a socket or receptacle, metallic end and side contacts upon said base, and means for forcing said side contact radially outward.

4. An attaching-plug comprising an insulating base adapted to be thrust endwise into a socket or receptacle, a metallic contact secured to one end thereof, a spring contact mounted in a channel in one side of said base, 60 and means for forcing said spring contact outwardly.

5. An attaching-plug comprising an insulating base having a cylindrical portion adapted to be thrust endwise into a socket or 65 receptacle and provided with a side channel, a metallic contact secured to the end of said base, a spring contact blade secured to said base and normally lying within said channel, and a key adapted to engage said contact 70 blade and force it outwardly.

6. An attaching-plug comprising an insulating base adapted to be thrust endwise into a threaded contact shell of a socket or receptacle, a metallic center contact mounted 75 thereon, a spring contact blade mounted upon the side thereof and provided with corrugations adapted to engage the threads of the contact shell, and means for moving said blade outwardly.

7. An attaching-plug comprising an insulating base provided with terminal plates, end and side contact members respectively connected to said plates, and a rotary key adapted to engage said side contact and 85 force it radially outward.

8. An attaching-plug comprising an insulating base having a reduced cylindrical portion provided on one side with a series of transverse ribs and a channel in the opposite 90 side, a center contact secured to the end of said cylindrical portion, and a movable corrugated contact blade secured in said channel.

9. A plug comprising a body of insulating 95 material, a contact carried thereby and adapted to engage one of the contacts of the socket, a movable contact carried by the body and adapted to engage the remaining contact of the socket, said movable contact 100 being formed with threads, and means carried by the plug to operate said movable contact to force the threads thereof into engagement with the threads of the socket.

In witness whereof, I have hereunto set my 105 hand this 20th day of August, 1903.

HENRY GEISENHÖNER.
